UNITED STATES PATENT OFFICE.

JOSEPH W. BUDD, OF NEW YORK, N. Y.

APPARATUS FOR BURNING PETROLEUM AND OTHER LIQUID HYDROCARBONS.

SPECIFICATION forming part of Letters Patent No. 391,018, dated October 16, 1888.

Application filed July 3, 1886. Serial No. 207,070. (No model.)

To all whom it may concern:

Be it known that I, JOSEPH W. BUDD, of the city and State of New York, have invented an Improvement in Apparatus for Burning Petroleum and other Liquid Hydrocarbons, of which the following is a specification.

The object of this invention is to heat the steam that passes into the generator to a higher temperature and regulate with facility the admission of combustible gases into the combustion-chamber, so that the intensity of the fire may be regulated without affecting the portion of the apparatus in which the gases are generated. I make use of a box or generator, into which the hydrocarbon liquid or vapor is admitted, and to which steam in a highly-superheated condition is also admitted and caused to commingle, so that the steam is decomposed by the carbon combining with the oxygen and liberating the hydrogen, and the latter mixes with the olefiant gases and is consumed beneath the generator and around the coils of pipe forming the superheater. The superheater is a series of coils of small pipes forming a jacket or case to the generator, so that the steam is subdivided and intimately heated, in order that as much steam as possible may be available for furnishing combustible gases to the fire. The gases that have been generated are passed through a pipe or pipes leading outside the furnace-chamber and through a cock of refractory material—such as asbestos—and returned into the fire chamber, so that the volume of flame in the fire-chamber may be varied at will.

In the drawings, Figure 1 is a general plan of the apparatus. Fig. 2 is a vertical section of the same at the line *x x*. Fig. 3 is a vertical section at the line *y y*, and Fig. 4 is a separate plan view of the pipes and regulating-cocks.

The generator A is in the form of a rectangular box, preferably made of plates bolted together, and within the same are pendent plates 22, upon which are adjustable partitions 3, held by bolts passing through slots, so that the distance between the lower edges of the partitions 3 and the bottom of the generator can be regulated as desired. These plates 22 and their respective partitions 3 divide the generator into a central and two side chambers. Into the central chamber the petroleum

or other hydrocarbon liquid or vapor is admitted by the pipe 4, and the superheated steam is also admitted into the same chamber 55 by jet-pipes 6789, that stand around the nozzle or end of the pipe 4, and hence the superheated steam issuing from the said jet-pipes comes directly into contact with the petroleum-vapors, and these remain together within 60 the central chamber of the generator, and the carbon combines with the oxygen of the steam, and the gases then pass below the partitions 3 into the outer chambers, and thence to the other parts of the apparatus next described. 65 By adjusting these partitions the gases are caused to pass as close to the heated bottom of the generator as consistent with an unobstructed flow of the same, and these partitions can be raised or lowered, as required. 70

The tubular legs B open into the side chambers of the generator near the top thereof. They are closed at their lower ends and stand upon the feet 10, and at D are slotted pipes connecting the pairs of legs, there being thimbles between the ends of the slotted pipes and the respective tubular legs and deflecting ends 11 (see Fig. 3) within the tubular legs, so that part of the gases passing down the legs will be directed into the slotted tubes and issue 80 from the slot and burn beneath the generator A and the coils hereinafter described, to heat the same. The lever projections 12 upon the tubes D allow of their being partially rotated to direct the issuing flames upon the proper 85 parts of the coils and generator. Ranges of perforations may take the place of the longitudinal slots.

There are cross-pipes 15 connecting the legs B with the horizontal gas-pipe E, that passes 90 from between the legs to the exterior of the casing or fire-chamber. This casing or fire-chamber may be of any desired size or shape. A portion of the same is shown at G.

Outside the fire-chamber the pipe E is provided with a T-connection to the returning gas-pipes H and K, and at L L' are cocks by which the flow of gases through the respective pipes can be regulated. These cocks are preferably made of asbestos or other refractory 100 material, so as not to be injured by the heat of the gases.

The pipes H and K pass back between the legs B, and to them are connected by coup-

lings or T's the burner-pipes N N', that form two or more groups extending out horizontally, or nearly so, and these pipes are of the desired length, according to the capacity desired for 5 the furnace, and such pipes are perforated or slotted upon their upper surfaces for the gases to issue and burn within the fire-chamber. By this improvement the extent of heating capacity can be varied by increasing or diminishing the length or number of the burner-pipes without otherwise changing the apparatus, and the height or volume of flame can be regulated by the cocks L L'.

In order to concentrate the flame from the 15 slotted tubes D upon the generator and at the same time to superheat the steam, I make use of a hood, M, formed of small sized pipes surrounding and at a small distance from the generator and placed close together to confine the 20 flame. This hood is composed of separate coils placed one above the other, and the steam supplied in a regulated quantity to the pipe P is subdivided and passed through the respective coils and becomes highly heated in 25 such coils, because the pipes are small, and the volume of steam passing through each coil is brought intimately into contact with the heat in the pipes of the coils, and the superheated steam issues by the respective jet-pipes 6 7 8 30 9; and in addition to these there are the coils R R', that are beneath the generator and connected to the branch pipes and coils, as hereinafter stated.

A convenient manner of subdividing the 35 steam and making the connections to the coils is to carry out the branch pipes 20 21 and 22 23 at opposite sides of the pipe P, and to lead these pipes to the respective coils or sections of the hood M in the manner illustrated in the 40 drawings, the coil 24 being connected at one end to the jet-pipe 6 and at the other end to the horizontal coil R and to the branch pipe 20, the coil 25, jet-pipe 7, horizontal coil R', and branch 22 being connected, the coil 26, 45 jet-pipe 8, and branch 21 and the coil 27, jet-pipe 9, and branch pipe 23 being connected, forming other channels for the steam. By 50 these various channels for the steam to pass and to be exposed to the action of the heat the desired volume of steam can be sufficiently 55 superheated to act in the desired manner in volatilizing and decomposing the petroleum or other hydrocarbon, and in consequence of the connections to the respective legs coming together in opposite directions the gases descending those legs commingle, and if there is any inequality in the production of the gas the mixing of the same will render the flames more uniform.

I do not herein lay claim to any of the separate devices that are set forth in a joint application of George D. Carroll and myself, filed November 16, 1885, Serial No. 183,030.

I claim as my invention—

1. The generator formed as a box and having within it the pendent plates 2 2 below the top, in combination with the partitions 3, extending downwardly from said plates, and means whereby said partitions may be adjusted, and the pipes for supplying into such generator hydrocarbon fluid and superheated steam, substantially as set forth.

2. The generator formed as a hollow metal box, and the pipes for supplying into the same hydrocarbon liquid and superheated steam, in combination with the tubular supporting-legs opening at their upper ends into the generator, the horizontal slotted pipes D between the pairs of legs B and opening into the same, so that gas is supplied from the generator to the flame that heats the same, the connecting-pipes 15, and pipe E, extending outside the fire-chamber, cocks for regulating the passage of gas, the return tubes H K, passing back into the fire-chamber, and the lateral burner-tubes extending out from the tubes H K, substantially as specified.

3. The combination, with the generator formed as a hollow box, and the supply-pipe for hydrocarbon liquid and the jet-pipes for superheated steam, of a hood composed of separate coils of small pipes placed closely together around the hood and the coils of pipe below the hood, and a supply-steam pipe and separate connections to the respective coils and connections from such coils to the jet-pipes within the generator, substantially as set forth.

4. The combination, with the generator formed of a hollow metallic box, and a pipe for supplying hydrocarbon into the same, of numerous jet-nozzles for superheated steam around the inner end of the carbon-supply pipe, a separate coil for each jet-nozzle and a connection from the same to the steam-supply pipe, and perforated pipes for the gases to pass through and burn below the generator, said coils being around and below the generator, so as to be exposed to the intense heat of the flame and superheat the steam, substantially as specified.

Signed by me this 18th day of June, A. D. 1886.

JOSEPH W. BUDD.
